UNITED STATES PATENT OFFICE.

CHARLES G. PFEIFFER, OF PHILADELPHIA, PENNSYLVANIA, ASSIGNOR TO SPECIALTY ENGINEERING COMPANY, OF PHILADELPHIA, PENNSYLVANIA, A CORPORATION OF PENNSYLVANIA.

PORTABLE LOADING MACHINERY.

Application filed May 15, 1926. Serial No. 109,227.

This invention relates to portable loading machinery useful, for example, in gathering material such as coal, gravel or sand from a ground pile and elevating the same to a suitable height to enable gravity discharge into wagons, bins or other receptacles. More specifically, my invention is concerned with loading machinery in which the standard type of gasoline tractor is used both for the purpose of portage and also to drive the conveyors by which elevation is effected.

The main object of my invention is to enable use of the power unit of the tractor to progress the machine very slowly for the purpose of urging the receiving end of the elevating conveyor into the material and to thereby render said conveyor self-feeding. But the ratio of the standard gearing equipment in the transmission mechanism of standard tractors is entirely too high for the purpose referred to. This drawback I overcome, as hereinafter fully disclosed, by provision of low-gear auxiliary drive means adapted to receive motion from the power take-off shaft of the tractor, and to transmit such motion at the proper reduced speed rate, directly to the propeller shaft of said tractor.

My invention is also concerned with provision of control means enabling progression of the machine to be governed independently of the actuation of the elevating conveyor and vice versa, as well as to means enabling the auxiliary drive means to be disconnected entirely so that the tractor may be operated through the standard transmission associated with its motor when the machine is to be moved about from place to place.

A further object of my invention is to secure the foregoing advantages in an auxiliary drive organization having the form of an attachment capable of being economically manufactured and easily adapted to standard tractors without entailing any changes whatever in them, either with regard to their construction or normal mode of operation.

In the drawings Fig. I is a side elevation of a tractor-impelled loading machine conveniently embodying my invention.

Fig. II is a perspective view of the rear end of the tractor with one of the bull wheels removed to enable showing of certain details of the auxiliary drive means to better advantage.

Fig. III is a view partly in plan and partly in section, of the forward portion of the auxiliary drive means.

Fig. IV is a sectional view taken as indicated by the arrows IV—IV in Fig. III.

Fig. V is a sectional view taken as indicated by the arrows V—V in Fig. IV.

Fig. VI is an elevation of the casing enclosing the speed reduction gearing embodied in the auxiliary drive mechanism, by which power is directly transmitted to the propeller shaft of the tractor.

Fig. VII is a staggered sectional view taken along the dot-an-dash line VII—VII in Fig. VI, and as viewed in the direction of the arrows thereon.

Fig. VIII is a cross section taken as indicated by the arrows VIII—VIII in Fig. VI; and

Fig. IX is a detail view showing the manner in which I secure one of the gears of the speed reducing train to the rear end of the propeller shaft of the tractor.

With reference first more particularly to Fig. I of these illustrations, the tractor is comprehensively designated by the numeral 15; and the same will be observed as of a well known standard construction comprising an internal combustion motor 16 which is supported by fore and aft wheels 17—18, whereof the former are steerable by a hand wheel 19, while the latter function as the driving or traction wheels. Supported by suitable uprights 20—21 attached at the front and back ends of the tractor 15, is a superstructure 22 which houses, in its downwardly inclined rear portion 22^a, an elevating bucket conveyor 23, and in its overhanging horizontal frontal portion 24,

a transfer belt 25 whereby the elevated material is carried laterally from the elevating conveyor 23 for discharge forward beyond the confines of the tractor 15. The endless side chains between which the buckets of the conveyor 23 are supported, run about sprocket wheels on upper and lower shafts 26, 27, and the transverse belt 25 about pulleys on shafts 28, 29; all suitably journaled in the superstructure 22 and driven in unison by power derived from the tractor 15 through the medium of a series of sprocket chain connections indicated at 30, 31, and 32. For the purpose of gathering in the material from a ground pile and ad-

vancing the same toward the conveyor 23, the lower shaft 27 of the elevating conveyor 23 is equipped at opposite ends with opposing feed screws 33—which are interrupted at various points by offset shoulders 34—after the manner shown and described in my application No. 80,188 filed January 9, 1926, addressed specifically to this feature.

The brief outline thus far given of the loading machine proper will serve to facilitate an understanding of the auxiliary drive mechanism of my invention and the purpose for which it is especially intended. In the complete assembly in Fig. I, this auxiliary drive mechanism is generally designated by the numeral 35, and, as shown to best advantage in Fig. II, involves use of a housing 36 which is bolted into place over the opening 37 through which access is had to the power take-off shaft 38 of the tractor, see Figs. III, IV and V. Within the housing 36 is journaled a short supplemental shaft 39 capable of being coupled with the power take-off shaft 38 of the tractor by a sliding clutch-sleeve 40 adapted to be controlled by a foot lever 41. The supplemental shaft 39 extends to the exterior of the housing 36 to take the drive sprocket pinion 42 for the chain 30, see Fig. I; while a worm 43 integrally formed on said shaft (Figs. III, IV and V) imparts motion to an intermeshing gear 44 on a line shaft 45 which has bearing at one end in the housing 36 and extends rearwardly along one side of the tractor 15 into a reverse gear casing 46 appended to the differential housing 47 at the back of said tractor, see Fig. II. As shown, in Figs. VI and VII, the casing 46 encloses a train of speed reduction gears 48, 49, 50, 51, 52 and 53 whereof the pinion 48 is fast on the line shaft 45 and the gear 53 fast on the rear end of the propeller shaft 54 of the tractor 15. To attach the gear 53 to the propeller shaft 54 and secure the reverse gear casing 46, I preferably proceed as follows: the usual cap plate protecting the roller bearing 55—in which the rear end of the propeller shaft 54 is journaled—is first removed, and the gear 53 made fast by splines or keys 55 after being screwed into position on the threaded portion 56 of said shaft. Obviously, the hub bore of the gear 53 is previously tapped in conformity with the threaded portion 56. The hub of the gear 53 is extended at 57 to allow room for the boss 58 of the reverse gear casing 46 which is bolted on in place of the discarded cap plate, use being made of the same securing screws 59—and socket holes that originally served said cap plate, see Fig. VII. The described arrangement, it will be seen provides an auxiliary drive (in the present instance reverse) for the tractor 15, the gears 48—53 of which are so

proportioned that the movement imparted to the machine is at a speed greatly reduced as compared to that obtained through use of the ordinary gear transmission of said tractor, and enables the feed means 34 at the lower end of the elevating conveyor 23 to be "nosed" into the ground pile of the material at a sufficiently slow rate to permit said conveyor to operate at full capacity without danger of stalling the tractor 75 motor.

In order to enable disconnection of the auxiliary reverse drive means just described, I mount the pinion 52 and associated wheel 51 of the reduction gear train 80 (Fig. VI) upon a stub-shaft 60 that is eccentrically journaled in the gear casing 46 and rotatable, by means of an attached hand lever 61 at the exterior, to withdraw the pinion 52 aforesaid from meshing engagement with the normally cooperating gear 53. The eccentricity and the allocation of the stub-shaft 60 is, however, such that meshing engagement between the gear 51 and the pinion 50 is not disturbed. 90 Thus, when the lever 61 is swung to the dot-and-dash line position in Fig. VI, the auxiliary drive is rendered idle by disconnection of the pinion 52 from mesh with the gear 53, thereby enabling the tractor 95 to be moved about from place to place by use of its customary transmission gearing.

For the purpose of governing the operation of the machine during loading, I provide a clutch 62 (Figs. II, III, and IV) 100 that is controlled by a hand lever 63 pivoted to a bracket 64 extending rearwardly from the housing 36, previously referred to. The clutch 62 is of the friction type and comprises reversely coned parts 65, 66 which are respectively secured to contiguous sections 45^a, 45^b of the line shaft 45, as best shown in Fig. IV. By the provisions just described, it will be apparent that the auxiliary gearing 48—53 may be rendered idle 110 notwithstanding continued operation of the chain 30 through which the elevating bucket conveyor 23 and the transfer belt 25 are driven.

Assembling of the auxiliary drive is facilitated through use of a connecting coupling, sleeve such as shown at 67 in Fig. III, between the section 45^b of the line shaft 45 and that portion 45^c thereof which extends into the gear casing 46. By virtue 120 of being pivotally connected at right angles to respective ends of the shaft sections 45^b, 45^c as shown, the coupling 67 acts after the manner of a universal joint with capacity to allow for slight disalignment between said shaft sections.

The operation of my invention is as follows: When the machine is to be moved from place to place, the clutch lever 41 is thrown to off position thereby discon- 130

necting the supplemental shaft extension 39 from the power take-off shaft 38, of the tractor 15 thus rendering the elevating conveyor 23, as well as to the auxiliary gearing 48-53, idle. The handle 61 at the back of the casing 46 also is thrown to off position at this time so as to disconnect the auxiliary drive gear 52 from the propeller shaft 54 of the tractor 15.

On the other hand, to prepare the machine for loading, the clutch lever 41 is first thrown to the on position for coupling of the supplemental shaft 39 with the power take-off shaft 38 of the tractor 15 and thereby setting the elevating conveyor 23 and the transfer belt 25 into motion. The reduction gearing 48-53 of the auxiliary drive means is thereupon made ready for action by movement of the lever 61 to the full line position of Fig. VI. Then, through shifting of the clutch 62 by means of lever 63, the machine may be backed into the ground pile as required to enable the buckets of the elevating conveyor 23 to take up the material. By slipping the clutch 62, the rearward progress of the machine may obviously be interrupted whenever necessary to prevent choking of the conveyor 23 and possible stalling of the power unit of the tractor 15.

Having thus described my invention, I claim:

1. In a loading machine embodying a tractor for portage, means comprising a worm drive clutchable to the tractor power take-off shaft, a reverse drive or train of reduction gears associated with the tail-end of the tractor propeller shaft, a line shaft co-ordinating said worm and reverse drives, and means whereby the respective drives may be disconnected when progression of the loading machine is to be effected by the tractor transmission.

2. In a loading machine embodying a tractor for portage, a supplemental shaft

and worm drive clutchable to the tractor power take-off shaft, a reverse drive or train of reduction gears one of which is threaded on and splined to the tail-end of the tractor propeller shaft, a line shaft co-ordinating said worm and reverse drives, and means whereby the respective drives may be independently disconnected for the purposes set forth.

3. In a loading machine embodying a tractor for portage, a supplemental shaft and worm drive clutchable to the tractor power take-off shaft, a reverse drive or train of reduction gears one of which is threaded on and splined to the tail-end of the tractor propeller shaft, a pinion in the train of gears mounted upon an eccentrically journaled stub-shaft having means for partially turning the same to withdraw said pinion from meshing engagement, a line shaft co-ordinating said worm and reverse drives, and means whereby the respective drives may be independently disconnected for the purposes specified.

4. In a loading machine embodying a tractor for portage, a supplemental shaft and worm drive clutchable to the tractor power take-off shaft, a reverse drive or train of reduction gears one of which is threaded on and splined to the tail-end of the tractor propeller shaft, a pinion in the train of gears mounted upon an eccentrically journaled stub-shaft having means for partially turning the same to withdraw said pinion from meshing engagement, a line shaft co-ordinating said worm and reverse drives a universal coupler intermediate the ends of said line shaft, and means whereby the respective drives may be disconnected, for the purposes specified.

In testimony whereof, I have hereunto signed my name at Philadelphia, Pennsylvania, this 7th day of May, 1926.

CHARLES G. PFEIFFER.
